2 Claims. (Cl. 123—117)

The present invention relates to an automatic adjustment of the ignition point for explosion engines. Automatic adjustments of the ignition point for explosion engines are known by which the location of the ignition point within the thermic cycle is adjusted by means of centrifugal governors which are correlated in function to the speed of rotation of the engine. The correlation is effected by means of springs which are located in the interior of the apparatus, for a certain fuel mixture, for a certain condition of the engine, and throttle opening. If there are changes in one of the mentioned conditions, it is necessary that the ignition be adapted to the new condition, if the maximum power of the engine is to be obtained without knocking. The correlating springs of the ignition systems determine a certain adjustment curve which cannot be changed without the disassembly of the apparatus, and so the relationships once established remain constant for each cylinder charge. Only a manual adjustment is possible. This may serve for a certain speed of rotation, but must continually be adapted to increases or decreases of the speed of rotation.

The object of the invention is a procedure whereby the adjustment of the ignition point of explosion engines is adapted to the existing working conditions, by making the timing of the ignition point dependent on the pressure conditions in the exhaust. There conditions prevail which are naturally dependent upon the speed of rotation and the charge. It is thus very advantageous to make use of both these already combined factors for effecting this automatic adjustment of the ignition point. Moreover, means can very easily be interposed which enables the ignition curve to incline more or less steeply as desired.

On the accompanying drawing, there is illustrated schematically, and only as far as is necessary for the understanding of the invention, an apparatus which permits carrying out the procedure according to the invention.

The exhaust manifold of the explosion engine is designated by numeral 1. Between this manifold 1 and the muffler 2, a tube 3 branches off, which leads to a filter 4, where entrained dust particles are caught. From this filter another tube 5 leads to an antechamber 6, to the sides of which are connected a pressure-sensitive member 7 (in the present example a cylinder with a piston 8) and another tube 9 which leads through

a throttle device 10 to the intake conduit 11 of the carburetor. In certain cases, the pressure-sensitive member may be connected to the intake 11 with the interposition of a throttle device here shown in dot and dash lines, by means of another tube 12.

The piston rod 13 of the piston 8 is here directly connected with the adjustment plate 14 of a distributor, upon which, as usual, the breaker is mounted.

It is now clear that the pressure prevailing in the exhaust pipe may be transmitted through the pneumatic connections 3, 4, 5 and 6 from this pipe to the pressure-sensitive member 7. Now the pressure will be proportionately greater as the charge in the cylinder and the speed of rotation of the engine increases. With fluctuating charge and varying speed of rotation there will be derived a combined relation which adapts itself advantageously to accommodate the adjustment of the ignition point accurately to the conditions prevailing at each instant. Accordingly now as it is wished to have the adjustment curve more or less steep, the antechamber 6 may be connected more or less with the intake conduit by means of the throttle device 10, and thus the relation to the condition of the engine adjusted at will without the automatic operation suffering thereby.

What is claimed is:

1. In combination with an internal combustion engine having intake and exhaust manifolds and an adjustable ignition system means for automatically adjusting the ignition in accordance with the variations in pressure of the intake and exhaust gases, and manually adjustable means for selectively causing one of said gas pressures to predominate over the other in its effect on the ignition adjustment.

2. In combination with an internal combustion engine having intake and exhaust manifolds and an adjustable ignition system, a pressure chamber, means connecting said chamber to the intake and exhaust manifolds whereby the pressure therein is a resultant of the pressure of the gases in said manifolds and a pressure responsive device operable by pressures within said chamber for adjusting said ignition system and throttling means in said connecting means manually operable to cause one of said gas pressures to have a predominating effect on the pressure in said chamber.
